UNITED STATES PATENT OFFICE.

ALFRED L. BERNARDIN, OF EVANSCVILLE, INDIANA.

BOTTLE-CAP.

1,244,413.

Specification of Letters Patent. Patented Oct. 23, 1917.

Application filed March 6, 1917. Serial No. 152,692.

To all whom it may concern:

Be it known that I, ALFRED L. BERNARDIN, a citizen of the United States, and a resident of Evansville, in the county of Vanderburgh and State of Indiana, have made certain new and useful Improvements in Bottle-Caps, of which the following is a specification.

My present invention relates generally to 10 bottle caps and more particularly to bottle caps for catsup bottles and the like, my primary object being to provide a bottle cap capable of sealing a bottle such as a catsup bottle, in the first instance, and of use as 15 the ordinary screw cap during the gradual using of the contents of the bottle after opening thereof and breaking of the seal.

In carrying out these objects in such manner as to bring about the advantage to be 20 hereinafter specified over bottle caps of generally similar nature, I provide the bottle in connection with which the cap is to be used with an annular shoulder below the threads thereof, and I provide a cap having threads 25 capable of engagement with the threads of the bottle in such manner as to completely pass the bottle threads when firmly in position, the cap having an internal sealing member for engagement with the bottle 30 mouth. Thus the cap is capable of inward movement on the bottle neck under pressure to compress the sealing member, which carries the cap threads substantially beyond the threads of the bottle neck, the cap having 35 at its inner end an extension the free edge of which is bendable into engagement with the inner edge of the shoulder of the bottle neck so as to thus hold the cap in position, and at the same time providing 40 for the breaking of the seal by removal of said extension and the subsequent use of the cap in cooperation with the threads of the bottle during the gradual use of the contents of said bottle, as ordinarily.

45 The invention consists in certain novel constructions, arrangements and combinations of parts as well as in the method of sealing as will be hereinafter more fully described and claimed.

50 Referring now to the accompanying drawing illustrating my improvements,

Figure 1 is a perspective view of a bottle neck provided with my improved cap,

Fig. 2 is a vertical section through the bottle neck of the cap illustrating the latter in operative connection before sealing,

Fig. 3 is a similar view with the parts in sealed position,

Fig. 4 is a horizontal section taken substantially on the line 4—4 of Fig. 3, and 60

Fig. 5 is a side view of the bottle neck as constructed for the use of my improvements.

In regard to the construction provided in my present invention it would appear that the cap with the sealing device connected 65 therein is fitted to the neck of the bottle and is initially interlocked therein by means of screw threads. Thereafter pressure is applied to any desired extent independent of the screw thread action by means of a 70 plunger 18 or in any other suitable manner and the sealing disk is compressed upon the lip of the bottle neck. This compressing action or sealing action it will be noticed is secured independent of the screw thread 75 action and when the disk is under this pressure it is locked to the neck of the bottle by bending the lower end of the cap beneath the annular shoulder. I thus have a process wherein the cap containing the seal 80 is initially interlocked with the bottle, the cap and sealing disk is subsequently submitted to pressure independent of the interlocking means and thereafter the cap is locked on the neck of the bottle by bending 85 its lower end beneath the annular shoulder. This is advantageous in that I am able to secure a strong sealing pressure and after the bottle has been unlocked by opening or otherwise releasing the portion in engagement with the shoulder the interlocking 90 means may be utilized to temporarily secure the cap in place during the use of the invention.

Referring now to these figures, and particularly to Fig. 5, I provide a bottle neck indicated at 10 and having threads 11 below its mouth 12, with an annular shoulder 13 below the said threads 11 for the particular purpose to be presently described.

100 The cap 14 provided by my invention may be formed of the usual stiff or hard metal

and has an inner sealing member 15 against its top 16, this sealing member being either in the form of a disk as shown or a ring, for engagement of the mouth of the bottle as 5 clearly indicated in Figs. 2 and 3, and may be constructed of various materials suitable in the formation of an air and liquid tight joint, the cap having intermediate threads 17 engageable with and completely beyond 10 the bottle neck threads 11 so as to thus clearly adapt the cap threads 17 for movement with the cap beyond the bottle neck threads when pressure is applied, for instance by a pressure member 18 as seen in 15 Fig. 3, in a suitable machine for this purpose, the action of which forces the cap inwardly upon the bottle neck, and compresses the sealing member 15 against the bottle mouth 12.

20 At its inner edge the cap as thus far described has an extension band 19 which is preferably formed of comparatively soft metal in order to adapt the inner free edge thereof to be flanged or rolled beneath the 25 inner lower edge of the bottle neck shoulder 13 as seen at 20 in Fig. 3, the opposite edge of the said extension being connected to the lower inner edge of the cap by a seam 21 which may be of any suitable type as for in- 30 stance, an inter-folded seam or a lap joint seam, but which is preferably of the bead seam type as shown in Figs. 2 and 3 in order that the cap will, upon complete removal of the band, remain as the usual cap for appli- 35 cation and re-application to the bottle neck in the regular way.

The ends of the band 19 are preferably joined by an inter-folded seal as seen at 22 in Fig. 4 in particular, one end of the band 40 having a tongue 23 projecting beyond the seam in order to provide for ready and complete ripping or tearing of the relatively soft band completely from the cap and from engagement with the bottle neck shoulder 45 13 in breaking the seal in the first instance.

When formed of a soft metal as described however, the band may be readily cut away from the bottle neck shoulder and a projecting tongue such as the tongue 23 as de- 50 scribed may be done away with.

It is obvious from the foregoing that in the sealing process the cap 14 is applied to the bottle by hand and screwed down so that the threads of the cap not only engage with 55 the threads of the bottle neck, but pass the same. The bottle head is then placed under a suitable machine including the pressure member 18 of Fig. 3, that compresses the sealing member 15 and the lower free 60 edge of the band 19 is rolled around the lower edge of the bottleneck shoulder 13 during the time the pressure is being applied, thus securely fastening the entire cap in sealed position. This seal is broken 65 when the package is opened by tearing away

the soft metal band 19 which leaves nothing but the screw cap so that the latter can be taken off and re-applied during the use of the contents of the bottle in the regular way.

It is obvious that by thus providing an extended band at the inner end of the cap connected by a seam to the cap, will avoid the necessity of making the entire cap from soft metal and consequently effect a con- 75 siderable saving in cost of the complete cap, and that for this reason as well as the combined structural features otherwise de- 80 scribed, I am enabled to provide a simple, inexpensive closure which combines a seal and a screw cap for use upon bottles the contents of which are emptied gradually and which therefore require a protecting clo- 85 sure during the use of the contents as well as an initial seal.

It is obvious furthermore that by the construction of a combined device of the character specified, I am enabled to entirely dis- 90 pense with the separate seal ordinarily re- required with the cap over the seal, which lat- 95 ter is utilized after the separate seal is re- moved, all with the exception of a cork washer or sealing member which is retained with my invention as above described.

It is to be appreciated that the cap may be 95 changed in certain respects over the particu- lars shown in the drawing, and may, if so desired, be pieced instead of seamless as shown, without interference in any respect with my invention as thus fully described. 100

I claim;

1. The combination with a bottle neck provided with threads and with an annular shoulder below the threads, of a cap containing an inner sealing member for engage- 105 ment with the bottle mouth and provided with threads for engagement with the threads of the bottle neck and to pass the same for movement therebeyond when pres- 110 sure is applied to the cap for compressing the said sealing member, and a connection band connected to the lower edge of the cap and projecting inwardly beyond the bottle neck shoulder for bending into engagement with the latter to hold the cap in sealed 115 position.

2. The combination with a bottle neck provided with threads and with an annular shoulder below the threads, of a cap containing an inner sealing member for engagement 120 with the bottle mouth and provided with threads for engagement with the threads of the bottle neck and to pass the same for movement therebeyond when pressure is applied to the cap for compressing the said 125 sealing member, a connection band connected to the lower edge of the cap and pro- jecting inwardly beyond the bottle neck shoulder for bending into engagement with the latter to hold the cap in sealed position, 130

and a bead seam connecting the cap and its extension whereby the latter may be wholly removed from the bottle and the cap.

3. The combination with a bottle neck 5 provided with threads and with an annular shoulder below the threads, of a cap containing an inner sealing member for engagement with the bottle mouth and provided with threads for engagement with the 10 threads of the bottle neck and to pass the same for movement therebeyond when pressure is applied to the cap for compressing the said sealing member, and a connection band connected to the lower edge of the cap 15 and projecting inwardly beyond the bottle neck for bending into engagement with the latter to hold the cap in sealed position, said band having an interfolding seam connecting its ends and having one of its ends provided with a tongue projecting from the 20 seam for the purpose described.

4. The combination with a bottle neck provided with threads, of a cap having an internal sealing member engageable with the 25 mouth of the bottle and provided with

threads which engage and pass the threads of the bottle neck for movement therebeyond when pressure is applied to the cap to compress the said sealing member, said cap and the bottle neck being provided with relatively engaging means when the cap is so compressed, to hold the latter in sealed position.

5. The combination with a bottle neck provided with threads, of a cap having an 35 internal sealing member engageable with the mouth of the bottle, and provided with threads which engage and pass the threads of the bottle neck for movement therebeyond when pressure is applied to the cap to compress the said sealing member, said cap and the bottle neck being provided with relatively engaging means when the cap is so compressed, to hold the latter in sealed position and including a cap carried part which 40 is removable from the cap to free the latter for coöperation with the threads alone in its 45 subsequent use.

ALFRED L. BERNARDIN.
